UNITED STATES PATENT OFFICE.

ARTHUR W. BURNHAM, OF GARDINER, MAINE, ASSIGNOR, BY MESNE ASSIGNMENTS, OF ONE-HALF TO FRED WILLIAMS, OF SAME PLACE.

MOP-WRINGER.

SPECIFICATION forming part of Letters Patent No. 393,355, dated November 27, 1888.

Application filed August 24, 1887. Serial No. 247,752. (Model.)

To all whom it may concern:

Be it known that I, ARTHUR W. BURNHAM, of Gardiner, in the county of Kennebec and State of Maine, have invented certain new and useful Improvements in Mop-Wringers; and I do hereby declare the following to be a full, clear, and exact description of the invention, such as will enable others skilled in the art to which it appertains to make and use the same.

10 My invention relates to an improvement in mop-wringers, and particularly to a class in which the wringing device is made a fixture to a scrub pail or bucket.

The object of my invention is to produce a 15 mop-wringer of the class above indicated that will be compact in form, reliable in action, and that may be produced at a low cost.

With this object in view my invention consists in certain features of construction and 20 combinations of parts, that will be hereinafter more fully described, and pointed out in the claims.

Referring to the drawings, making a part of this specification, Figure 1 is a side elevation 25 of the working mechanism and its supporting tripod-stand in position in a pail, the sides of the latter being broken away to show the device which exhibits the wringing-rollers at their point of farthest separation. Fig. 2 represents a side elevation of the wringing-machine in position in a pail, the latter being broken in section to show the wringer apparatus, which latter is in closed adjustment. Fig. 3 is a front elevation of the wringing device with the body of the pail removed. Fig. 35 4 is a longitudinal section of the base-plate. Fig. 5 is a detached view of the rock-arm. Fig. 6 is a plan view of the base-plate, showing standard K in section.

40 The wringing mechanism is placed in a water-pail, B, and is connected to a tripod, A, which is adapted to fit upon the underside of the pail and afford a support to it. The tripod A has two laterally-diverging legs, A', attached to an enlarged joining-plate, A². This plate A² is widened, and has a flat top surface that extends a proper distance to afford a support for the pail-bottom in conjunction with the horizontal upper surfaces of the legs A'. 45 50 The third leg, A³, of the tripod A is extended

in line with the terminal end of the joining-plate A² and is an integral extension of the same. The leg A³ is made to extend toward the front or nearest side of the pail to the operator, and is projected horizontally a greater length than the legs A' for a purpose that will be made apparent. 55

Upon the inner surface of a pail, B, that is properly placed on the bearing-faces of the legs A', plate A², and extended leg A³ of the supporting tripod A, the base-plate B' is seated. A bolt, a, is made to project from the lower surface of the base-plate just mentioned to penetrate a hole of proper size made in the bottom of the pail B to receive it, and this bolt 60 is also inserted through a hole in the joining-plate of the tripod A to afford means for securely attaching the tripod, pail, and base-plate together by the proper adjustment of a nut, a', on the threaded end of the bolt, the nut 65 bearing firmly against the lower surface of the tripod about at the point of junction of the three legs of this tripod A. 70

The base-plate B' consists of a flat piece of metal, preferably of a rectangular form—that 75 is, perforated at proper points, 1 2, to lighten it—and has vertical ribs 3 4 formed integral with its side edges. At the forward end, or end nearest the leg A³, of tripod A this base-plate is provided with lugs 5 6, which are 80 notched to form a half-round groove across their top faces. These grooves 7 8 are from their location parallel to the side surfaces of the ribs 3 4 of base-plate B'. At the rear or opposite end of the base-plate B' there are two 85 ears, 9 10, made integral with the terminal ends of the ribs 3 4 of this plate, and outwardly projected from them at right angles to the side surfaces of the ribs. The ears 9 10 are perforated through their bodies, these holes being 90 about in line with the grooves 7 8, that are cut in the top edges of the lugs 5 6, that project from the front end of the base-plate B'. 95

The wire bail-clamps F F' are intended to be supported by their ends in swinging adjustment with the sides of the base-plate B'. To effect this the rear ends, b, of these clamps are bent to enter the holes in the ears 9 10 at rear end of base-plate B', and the forward ends of these bail-clamps are bent nearly at a right 100

angle to the forward vertical limbs, F^2 , of these clamps, so as to provide journals e from the wire bodies of the clamps that rest in the grooves 7 8 in lugs 5 6 and allow the clamps 5 F^2 to rock on these points of support. The projecting ends of the bail-clamps F^2 , that are integral extensions of the journals e of said clamps, are bent and wound around the outer ends of these journals to produce spiral springs 10 e' , which springs are intended to afford a limited yielding action to the clamps F^2 when they are in use.

Upon the forward end of the base-plate B' there are two lugs, 11 12, made to project from 15 the sides of the base-plate B' , that are similar in form to the lugs 5 6, previously described. They are situated near to these latter-named projections 5 6, and are parallel to them. The lugs 11 12 are so relatively located as to allow 20 the grooves on their lower surface to receive the wire journals of the bail-clamps F^2 , and by contact therewith prevent upward displacement of these swinging clamps.

Upon the upper surface of the forward end 25 of the base-plate B' , at the corners of the same, two vertically-projecting limbs, d , are formed integrally with it. These are intended to brace and re-enforce both of the upright parallel standards G' . The standards G' just mentioned are provided each with a lip or short lateral flange, g , which latter have bearing contact with the sides of the vertical limbs d , and partially embrace the same to lock the limbs and standards together, this lock being rendered secure by the proper adjustment of the nuts h' , which are adapted to fit the lower threaded ends of these standards G' , the rounded and threaded ends h of the standards passing through perforations in the body 30 of the base-plate B' made to receive them. The standards G' are preferably given a forward inclination, so as to conform substantially to the flaring inner surface of the pail B , which will economize space in the pail and allow a 35 wider divergence of the swinging roller J . The standards G' are braced by the cross-bar e , which is preferably cast integral with the standards. At the upper terminations of the standards an integral roller-supporting 40 bracket, G^2 , is located. This bracket lies in a plane parallel to the bottom of the pail B , and has its ends G^2 bent at right angles to the main portion to receive between them the ends of the roller I .

55 The roller I is preferably made of wood of proper hardness, and has wear-plates I' affixed to its ends, these plates being perforated centrally to receive the bodies of stout screws f , which are inserted through holes made in the 60 ends G^2 of the bracket G^2 , these screws affording cheap and reliable pintles or journals for the roller I , the wear-plates I' giving support to the screw-bodies and preventing them from becoming loose or the roller ends being worn 65 away. A mating roller, J , of the same length and diameter as the roller I , is mounted upon the single standard K , the upper end of which

is constructed with a bracket, K' , of similar form to that of the bracket G^2 , which bracket K' is attached to afford revoluble support to 70 the roller J by screws i , which penetrate the ends of this roller, the ends of the roller J having wear-plates k , when wearing away to prevent wearing away of the ends, these plates k being duplicates of the plates I' , that protect 75 the ends of stationary roller I . The swinging standard K has a bifurcated foot-piece, K^2 , the parallel jaws K^2 of which are such a proper distance apart as to loosely bear with their inner sides against the outer surface of the vertically-projecting ears m , to which they are pivoted, and which lugs are made integral with the upper edges of the ribs 3 4 of the base-plate B .

Upon the forward end of the rocking bar L extends 85 between the parallel standards G' and projects slightly forward of the same. It is slotted at this end, and has two eyes, o , formed from the parallel strips of material left. These eyes or perforated bosses are adapted to receive between them the lower end of the link-bar M , which is pivoted to them, and also at its upper end to the rock-arm M' . The rock-arm M' is provided with two parallel jaws, P , near its center (considered lengthwise) to engage 90 the top end of the link-bar M , and has its end that connects to the bracket G^2 made T -shaped to engage with it by a peculiar hinged joint, that will now be described.

Upon the top surface of the bracket G^2 two 100 hooks, q , are formed, that project their curved free ends rearwardly. The space between these hooks q is sufficient to allow them to receive the notched ends of the integral bar M^2 of the T -shaped head formed on the rock-arm 105 M' . The portions of bar M^2 which engage the hooks q are rounded to produce journals, and the adjacent projections, q' , act as guards to prevent the disconnection of the bracket and rock-arm, while a rolling connection is established between these pieces, and the rock-arm 110 M' is allowed to vibrate when pulled downwardly by its outer end. The outer end, M^3 , of the rock-arm M' is forked and has the two limbs r of the bifurcated end turned up to form 115 retaining guards.

A depending treadle-rod, N , has its top end made T -shaped to enter the slot between the upturned limbs r of the crotched outer end of rock-arm M' , and engage with its cross-bar s 120 the curved limbs r , which latter serve to hold the parts in hinged engagement and permit the vertical depression of the rod N .

A foot-plate or treadle-piece, N' , is adjustably attached to the treadle-rod N by a set-screw, t , so as to permit the foot-plate to be properly adjusted for height and allow an increase of travel to be given to the treadle, if necessary, to more forcibly close the swinging roller J against the revolving but stably-located roller I .

A guide-rod, O , is erected from the top of leg A^3 of the tripod A , and is made to enter a perforated ear formed on the side of the boss

⁵ of the foot-plate N', and thus steady the treadle-rod and its foot-plate when it is operated by the application of the foot of a user of the device.

¹⁰ The rear end of the rocking bar L is projected beneath the standard K and has bearing contact with the depending short arm P, that is an integral projection from the bifurcated lower end of this swinging standard.

¹⁵ Upon the top surface of the rocking bar L the curved plate-spring R is affixed by one end, the free end R' of the same being made to forcibly bear against the swinging standard K and hold it rearwardly projected when the device is not in use as a wringer. This action of the spring R will seat the bifurcated lower end of the standard K upon the adjacent top edges of the ears 9 10, that project from the side ribs of the base-plate B', and the rear ²⁰ roller, J, that is supported by the standard K, will be separated sufficiently from the other roller, I, to allow a mop-cloth to be freely inserted between the rollers into the water with which the pail is partially filled.

²⁵ The forward arms, c', of the wire bail-clamps F F', that are extended beyond the spiral springs c, are bent inwardly at right angles to the journals c, and are made to engage the lower end of the link-bar M, they being inserted in adjacent holes made through the lower portion of the link-bar that projects below its point of hinged connection with the rocking bar L. This connection of the bail-clamps F F' with the link-bar M will cause the depression of the foot plate N' to forcibly close the bail-clamps toward each other, and at the same time force forward the swinging standard K and its roller J, so that the mop-cloth that has been introduced between these two ³⁵ sets of compressors and first washed in the contained water in the pail B may be clamped sidewise by the clamps F F', and also by the forward movement of roller J. The simple withdrawing of the mop from the pail and a compression of the clamps F F' and roller J by pressure of the foot of the operator upon the foot-plate N' will effectually remove all the water from the cloth, as the gathering action of the bail-clamps F F' will force the cloth ⁴⁵ into a compact mass and strip the water from the cloth, while the rollers perfect the wringing operation.

It should be stated that the bearing ends of the legs of the tripod A are provided with ⁵⁵ elastic base-blocks T, upon which the water-pail and entire device are supported. This provision will prevent the metal feet from scratching a floor, and the extended bearing afforded by the tripod will support the device firmly ⁶⁰ and allow it to rest secure upon any uneven surface it may be placed upon. The gum blocks T are inserted in vertical perforations ^u, made in the feet of the tripod.

⁶⁵ Slight changes might be made in the construction of this device without exceeding the

scope of my invention; hence I do not limit myself to the exact forms herein shown; but,

Having fully described my invention, what I claim as new, and desire to secure by Letters Patent, is—

⁷⁰ 1. In a mop-wringer, the combination, with a water-pail, a rigidly secured roller-standard, a roller journaled in the upper end of said standard, a vibrating standard, and a rocking bar engaging the vibrating standard, of a link-bar connected to the rocking bar, a rock-arm attached to the link-bar, and means for actuating the rock-arm, substantially as set forth.

⁷⁵ 2. In a mop-wringer, the combination, with a base-plate, standards, and rolls mounted on the standards, of two swinging bail-clamps normally held in open adjustment, a rocking bar for bringing the rolls together, a link-bar connected to the rocking bar, a rock-arm attached to the link-bar, and means for vibrating the arm and closing the bail-clamp, substantially as set forth.

⁸⁰ 3. In a mop-wringer, the combination, with a base-plate, a roller-standard fixed to one end of said base-plate, a swinging standard pivoted to the other end of said base-plate, and rollers journaled in the standards, of two clamps located at right angles to the rollers and a rocking bar and arms connecting the movable standard and clamps, whereby they ⁸⁵ are actuated simultaneously, substantially as set forth.

⁹⁰ 4. In a mop-wringer, the combination, with a base-plate, a rocking bar fulcrumed upon the base-plate, a fixed upright roller-standard, a standard adapted to swing on the base-plate, two rollers, and a plate-spring that engages the rocking bar and swinging standard, of a link-bar, a rock-arm, a treadle-rod, and an adjustable foot-plate, substantially as set forth.

⁹⁵ 5. In a mop-wringer, the combination, with a base-plate, a fixed standard, a swinging standard, rollers journaled in said standards, a rocking bar, and a spring attached to said bar and bearing against the rocking standard, of clamps located at right angles to the rollers and arms connecting the rocking bar and clamps, whereby the latter and the swinging standard are operated simultaneously.

¹⁰⁰ 6. In a mop-wringer, the combination, with a tripod, a base-plate, and a water-receptacle, of two bail-clamps supported on the base-plate to swing toward each other, spiral springs formed upon the journaled ends of the bail-clamps, a fixed frame that supports a roller, and a swinging standard that supports a mated roller, substantially as set forth.

In testimony whereof I have signed this specification in the presence of two subscribing witnesses.

ARTHUR W. BURNHAM.
